UNITED STATES PATENT OFFICE

157,652

AIRPLANE KITE

Earl M. Whitehurst, Portsmouth, Va.

Application June 7, 1948, Serial No. 146,795

Term of patent 14 years

(Cl. D34—15)

To all whom it may concern:

Be it known that I, Earl M. Whitehurst, a citizen of the United States, residing in the city of Portsmouth, county of Norfolk, and State of Virginia, have invented a new, original, and ornamental Design for an Airplane Kite, of which the following is a specification, reference being had to the accompanying drawing, forming part thereof, and in which,

Figure 1 is a bottom plan view of the airplane kite, showing my new design; and

Figure 2 is a side elevation thereof.

I claim:

The ornamental design for an airplane kite, as shown.

EARL M. WHITEHURST.
